DISPOSABLE CATHETER ADAPTER PACKAGE OR THE LIKE

Robert L. McWayne, Burlingame, Calif.
(725 2nd Ave., San Francisco 7, Calif.)

Filed July 23, 1962, Ser. No. 71,003

Term of patent 14 years

(Cl. D83—1)

FIG. 2

FIG. 3

FIG. 1

FIG. 4

FIG. 1 is a perspective view of a disposable catheter adapter package, showing my new design.

FIG. 2 is a top plan view looking at the top of FIG. 1;

FIG. 3 is an elevational view with a quarter section of only the capped capsule removed to illustrate the package more clearly; the section removed being indicated by the lines 3—3 in FIG. 2; and

FIG. 4 is a bottom view looking up on FIG. 3.

The side of the package opposite to that appearing in FIG. 1 is identical to that shown in FIG. 1.

The characteristic features of my design for the catheter adapter package disclosed, reside in the specific configuration of the cap and capsule member, as shown.

I claim:

The ornamental design for disposable catheter adapter package or the like, substantially as shown and described.
